STIFFENER FOR SOFT COLLARS

Filed Aug. 18, 1928

INVENTOR.

BY Jose Sarandeses
Colton Polansky
ATTORNEY

UNITED STATES PATENT OFFICE

JOSE SARANDESES, OF NEW YORK, N. Y.

STIFFENER FOR SOFT COLLARS

Application filed August 18, 1928. Serial No. 300,467.

This invention relates generally to collars, and has more particular reference to a novel soft or semi-soft collar with reinforced tips.

The invention has for an object the provision of a device of the class mentioned, which is of simple durable construction, desirable and efficient in action, and which can be manufactured and sold at a reasonable cost.

The invention proposes the use of cloth material formed to present pockets and secured on the inner side of the tips of a collar. Stiff reinforcing sheets are placed in these pockets and serve for preventing bending and creasing of the tips. It is pointed out that the tips and the front portion of a collar usually crease and bend more readily than other portions, and this is especially true if the collar is soft. The instant organization acts for preventing this undesirable creasing, and in doing so does not add material weight to the collar, nor in any way interfere with the wearer thereof.

For further comprehension of the invention, and of the object and advantages thereof, reference will be had to the following description and accompanying drawing, and to the appended claims in which the various novel features of the invention are more particularly set forth.

In the accompanying drawing, forming a material part of this disclosure:—

Fig. 1 is a perspective view of a collar constructed according to this invention.

Fig. 2 is an enlarged fragmentary detail side elevational view of the inner side of one end of the collar in completely opened position.

Fig. 3 is a side elevational view of the inner side of the collar in completely opened position.

Fig. 4 is a vertical sectional view, taken on the line 4—4 of Fig. 2.

Fig. 5 is a horizontal sectional view, taken on the line 5—5 of Fig. 2.

Fig. 6 is a view similar to Fig. 4, but illustrating a modified form of the device.

Fig. 7 is a view similar to Fig. 3, but illustrating another modified form of the device.

Fig. 8 is a sectional view, taken on the line 8—8 of Fig. 7.

The reference numerals 10 indicate generally the tips on a collar having a front portion 11 and an integral collar band 12 with aperture 13 for collar buttons. The front portion 11 and the band 12 connect at their tops when the collar is in bent condition as shown in Fig. 1, that is with these parts adjacent each other.

Fig. 2 shows the inner side of the collar and dot-dash line 14 the line of bending of the collar. Pockets 15 are secured on the collar at the tips 10 and on the said inner side, and consist of cloth material bent on one side 16 and then sewn on this side, the opposite side 17 and the bottom side 18 onto the collar. The top side of the pocket has a flap 19 which is also sewn onto the collar. A reinforcing stiff sheet 20 is inserted in each of the pockets, this sheet being preferably made of celluloid.

The sides 16 and 17 are inclined for forming the pocket large at its bottom side 18 and smaller at its top side, and the reinforcing sheet 20 is similarly shaped. The small top 75 of the pocket serves the purposes of holding the reinforcing strip 20 against displacement. The reinforcing strip 20 should be flexible so as to be bendable for removing from the pocket.

In Fig. 6, a reinforcing sheet 20^a is shown with a curved top edge 21 for reinforcing the bend of the collar at the junction of the front 11 and the band 12. The dot-dash lines 22 indicates the collar band 12 in bent down position.

The modified form of the device illustrated in Figs. 7 and 8 discloses a reinforcing strip 23 provided with a snap fastening socket 24 at one end for pivotally mounting it upon a snap fastener stud 25 secured on the front side of the pocket 15, and the other end of the strip 23 is formed with serrations 26 engaging in loose threads 27 on the rear side of the pocket 15 and arranged in an arc coaxial with the pivot point of the strip 23. The strip 23 may be bent for disengaging the serrations 26 from the threads 27, and then moved for changing the inclination of the strip and thereafter allowed to straighten 100

and reengage the loose threads. The pivot point of the strip 23 is as near the corner of the tip 10 as possible. The position of the strip may be changed as just stated for adjustment to prevent creasing of the tips at portions, creasing due to individual reasons of the wearer of the collar.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a soft collar, a pocket for receiving a reinforcement strip, a reinforcement strip within the pocket and pivotally mounted at one end on the material forming the pocket and having its opposite end serrated, and loose stitches on the material forming the pocket and arranged in an arc coaxial with the pivot point of the strip for receiving the serrated end and holding the strip in desired angular positions.

2. In a soft collar, a pocket for receiving a reinforcement strip, a reinforcement strip within the pocket and pivotally mounted at one end on the material forming the pocket, and loose stitches on the material forming the pocket and arranged in an arc coaxial with the pivot point of the strip for receiving the free end of the strip and holding the strip in desired angular positions.

In testimony whereof I have affixed my signature.

JOSE SARANDESES
